United States Patent Office.

ALEXANDER MCPHERSON, OF SANTA CRUZ, CALIFORNIA.

Letters Patent No. 97,948, dated December 14, 1869.

IMPROVEMENT IN THE CONSTRUCTION OF BUILDINGS.

The Schedule referred to in these Letters Patent and making part of the same.

To all whom it may concern:

Be it known that I, ALEXANDER MCPHERSON, of Santa Cruz, county of Santa Cruz, State of California, have invented an Improved Construction of Stone, Brick, and Adobe Buildings; and I do hereby declare the following description and accompanying drawings are sufficient to enable any person skilled in the art or science to which it most nearly appertains, to make and use my said invention or improvements without further invention or experiment.

My improvements relate to the construction of stone, brick, adobe, and other buildings, in which mortar is used for binding together the material of which the walls are composed; and

It consists in placing between the courses of brick, stone, or other material, at regular or irregular intervals, according to the nature of the wall, layers of lath, strips of wood, or thin metal, in such a manner as to bind the wall in every conceivable direction.

It also consists in placing these laths, strips of wood, or thin metal, vertically in the masonry of the wall, so as to bind it in the opposite direction, and by this means render the walls strong and substantial, and proof against shocks of earthquake.

In order to more fully illustrate and describe my invention, reference is had to the accompanying drawings, forming a part of this specification, in which—

A, B, and C, show my manner of binding together the foundation,

D, E, F, and G, show my method of placing the laths, to bind the walls together.

In beginning to construct a building of any of the materials above described, I first commence by laying a broad foundation, A, in order that the subsequent walls may have a firm hold upon the ground, and be braced against becoming overbalanced at the top.

After laying several courses of the brick or stone, I place lath, strips of wood, or thin strips of metal, a, longitudinally with the wall.

I prefer common plasterers' laths, as they will answer every purpose, and can be obtained at a small cost. When I use these laths, I preserve them from rot, by boiling them in brine, or other preservative solution.

The figure marked A represents the manner of laying the first series of lath.

It will be seen that the outside laths extend from end to end of one wall, while the middle laths only extend half way across the wall, which stands at right angles to it, and the inside laths extend only to the inside line of this wall.

The ends of the laths which are laid upon the opposite wall, or wall which stands at right angles to the

first, meet the laths which have already been laid, thus binding the angle together each way.

The laths are laid in mortar, similar to the usual manner of laying bricks, and a thin coat of mortar placed upon them, into which the next course of bricks is laid.

The foundation-wall is then continued in the usual manner, each course of bricks being set in a short distance, so as to cause the walls to become of less thickness, as they rise.

After several courses of brick have been placed upon the lower part of the foundation, I then lay in mortar another course of lath, as shown at B, so as to cross the wall diagonally to the direction of the laths on A, the angle formed by the intersection of the walls being bound together by laths laid at an angle to the sides.

A third series of brick courses is then laid, tapering, as above described, upon which I place the laths diagonally across the wall, as shown at C, their direction being angularly across the laths upon the series B.

This operation is continued in the same manner, until the foundation is completed, when I begin the regular wall of the building, which is built as above described, of several courses of brick laid upon the foundation, and upon which said laths are placed first, as shown at D, in which the laths are laid longitudinally with the wall, those upon one wall extending entirely across the angle formed by the intersection of the two walls.

After another series of brick courses, I again apply the laths longitudinally, extending then entirely across the angle on the side opposite to that in which they were extended in D, thus allowing them to cross one another at right-angles at the corners.

Another series of brick courses, and I apply the laths diagonally across the wall, as at F, and in the next upper course of laths, I also apply them diagonally to the wall, but extending across in an opposite direction to those on F, in the manner shown at G.

In this manner the walls of a building can be so firmly bound together and tied, that it cannot be injured by even the most violent upheaval of the earth.

In order to keep the walls from being moved sideways from their position, that is, to prevent the result which would be caused by a sudden jerking of the earth, and which is usually found to be a movement of the upper part of the wall in one direction, and the lower part in another, I place between the bricks, at irregular intervals, upright laths or strips, or rods of metal, around which I place the brick-work. These vertical laths serve to bind the wall, and prevent its parting from any cause.

Walls laid and bound together in this manner can be built at the same cost as walls constructed in the ordinary manner, of brick, stone, concrete, or adobe, while their value will be greatly in advance, especially in countries subject to earthquakes.

Having thus described my invention,

What I claim, and desire to secure by Letters Patent, is—

Binding together the different parts of foundations and walls of brick, stone, concrete, adobe, or other

similar material, by interlaying through the work, in one or in several directions, strips of wood or metal, substantially as and for the purpose herein set forth.

In witness whereof, I have hereunto set my hand and seal.

ALEXANDER McPHERSON. [L. s.]
